UNITED STATES PATENT OFFICE

95,201

DESIGN FOR AN ASH TRAY

William J. Butts, Littleton, Colo.

Application January 24, 1935, Serial No. 55,036

Term of patent 7 years

To all whom it may concern:

Be it known that I, William J. Butts, a citizen of the United States of America, residing at Littleton, in the county of Arapahoe and State of Colorado, have invented a new, original, and ornamental Design for an Ash Tray, of which the following is a specification, reference being had to the accompanying drawing, forming part hereof.

The drawing illustrates a perspective view of the design.

I claim:—

The ornamental design for an ash tray, as shown.

WILLIAM J. BUTTS.
